PLUG CLOSURE

Wilbur H. Armacost, New York, N. Y., and Ralph M. Swartz, Bogota, N. J., assignors to The Superheater Company, New York, N. Y.

Application August 29, 1930. Serial No. 478,604

10 Claims. (Cl. 137—76)

Our invention relates to closure operating means and aims to provide an arrangement for holding a plug firmly against a seat and which permits removal and replacement of the plug 5 in minimum time.

Pipe stills and other common types of fluid heaters have large numbers of joints which must be closed tightly when in use to prevent leakage of fluid under high pressure and which must 10 be opened from time to time for cleaning the inner surface of the tubes. The quicker the individual joints can be broken and remade, the less time the apparatus need remain out of use for cleaning and inspection. In typical apparatus 15 the plugs are forced against their seats by threaded bolts which are operated by long handled wrenches to obtain sufficient leverage for making the joints sufficiently tight. The long handled wrenches are, however, clumsy so that 20 they can not be handled quickly and the operators of pipe stills and like apparatus have long desired an arrangement for the purpose in question adapted to be set up by less clumsy tools.

25 It is common, moreover, in pipe stills and like apparatus to give the seats and plugs a very gradual taper so that they wedge together with very high pressure. Difficulty, therefore, is often experienced in removing the plugs from their 30 seats, thus further extending the time the apparatus is out of use.

It is an object of our invention to provide an arrangement for overcoming the above mentioned difficulties.

35 The novel features of our invention will be pointed out in the appended claims. The invention itself, however, together with further objects and advantages, will best be understood 40 from the following detailed description of a closure embodying our invention, taken in connection with the accompanying drawing in which

Fig. 1 is an elevational view, partly in section, illustrating an H-type fitting connecting the ends of two tubes such as are used in pipe stills and like apparatus.

45 Fig. 2 is an end view, partly in section, of the arrangement shown in Fig. 1, the section being taken on the line 2—2 of Fig. 1.

50 Fig. 3 is a sectional view on an enlarged scale of a cam member appearing in Fig. 1.

Fig. 4 is a sectional view on an enlarged scale 55 of the plug shown in Fig. 1.

Fig. 5 is a fragmentary elevation of the plug shown in Figs. 1 and 4.

Referring to the drawing more in detail, 10 and

12 are two tubes through which it is desired to pass fluid in series and under pressure and for which purpose tubes 10 and 12 are connected by a suitable fitting 14. Fitting 14 serves as a return bend and is illustrated as an H-type fitting into which the ends of tubes 10 and 12 are rolled and which has an inner passage 16 through which fluid may flow from one tube to the other. To permit cleaning or inspection of the interior of the two tubes 10 and 12, fitting 14 has apertures therein in alignment with the tubes 10 and 12, one of said apertures being shown in Fig. 1 as defined by an inwardly tapering seat 18 and closed by a plug 20 having a tapered surface 19 complementary to that of seat 18 and adapted to cooperate therewith to close an aperture in the fitting 14. For forcing plug 20 against seat 18, we have illustrated an arrangement known in part, but the known parts of which, however, 60 form a part of our novel combination. The known arrangement just mentioned comprises an outwardly projecting skirt 22 having internal lugs 24, 24 adapted to cooperate with a yoke member 26 which carries a threaded bolt 28 65 therein for applying pressure to the plug 20. When in the operative position shown in Figs. 1 and 2, the ends of the yoke piece 26 engage the inner faces of the lugs 24 to resist the strain 70 set up by the bolt 28.

Instead of having the bolt 28 bear directly against the plug 20 as in the usual arrangement, we interpose between the inner end of bolt 28 and the outer end of the plug 20 a cam piece 30. The outer face or end of part 30 is shown 80 as recessed at 32 to receive the end of bolt 28 and its inner face or end is formed into a helix 34 extending entirely around it near the outer edge of the piece. Helix 34 works against a complementary helix 36 which is formed on and extends around the adjacent end of the plug 20. Preferably the pitch of helices 34 and 36 is greater 85 than that of the thread on bolt 28 and, as shown at 38 and 40, the adjacent ends of parts 20 and 30 are cut away or relieved so that the radial 90 width of the surfaces 34 and 36 is not great. The parts 20 and 30, moreover, have one a central projection 42 and the other a central recess 44 adapted to fit together to center one with respect to the other so that the surfaces 34 and 36 95 can be quickly brought into proper operating relationship in assembling the apparatus. It will be seen, therefore, that a plug 20, in accordance with our invention, may be forced against its seat by the action not only of the helical 100 threads on the parts 26 and 28, but also by the 105 threads on the parts 26 and 30.

helical surfaces 34 and 36 on the parts 20 and 30.

It is anticipated that, after the parts have been assembled somewhat loosely by hand, the bolt 28 will be set up by means of a wrench

5 of moderate size and length which can be re-
volved rapidly and the plug 20 will then be
forced further against its seat by turning the cam
piece 30, leaving little, if any, work to be done
on bolt 28 with a long, heavy wrench. For turn-
10 ing the cam piece 30, such piece is provided with
a finger 46 which projects laterally through a
slot in the skirt 22 having side edges 48, 48. A
slot such as that having edges 48 permits the
arm 46 to project laterally, as shown, beyond
15 the skirt 22 where it may be struck readily by a
hammer to turn piece 30 forcibly and thereby to
wedge lug 20 snugly against seat 18. The slot
having edges 48 may be such as to permit the
arm 46 to turn from 30 to 90 degrees, depending
20 upon the requirements of the installation. In
order to economize space, the slot for arm 46 is
so placed that the arm 46 lies substantially in the
plane of passage 16 and projects in the direction
from pipe 10 toward pipe 12.

25 The angle of the surfaces 34 and 36 to their axis
of rotation should, of course, be less than the an-
gle of friction of steel when parts 20 and 30 are
of steel, as is usually the case. When other ma-
terial is used for these parts the angle should be
30 designed so that it will not exceed the angle of
friction for the material used. It will be seen
that the radius of the surfaces 36 and 34 can be
made much greater than that of the bolt 28 in the
yoke 26 on account of the large size of parts 20
35 and 30 compared to part 28 and, for a given angle
of inclination to the axis of rotation, the pitch
of the surfaces 34 and 36 can therefore be much
coarser than that of the bolt 28 so that by turn-
ing the part 30 through a given angle, the plug
40 20 will be moved a much greater distance with
respect to its seat than can be done by turning
the bolt 28 through the same angle, assuming a
somewhat similar angle of inclination to the axis
of rotation for the helical surfaces of both the
45 part 30 and the bolt 28. As the wedging effect
of the two helical surfaces depends upon the angle
of inclination, it will be seen that, for a given
pressure on the plug 20, our arrangement per-
mits the plug to be forced against its seat much
50 more rapidly than if the entire movement were
produced by a bolt such as 28.

In order that the plug 20 may be removed from
the tapered seat 18 with maximum rapidity, we
55 have shown plug 20 as having thereon a laterally
extending arm 50 which normally is spaced from
the outer surface 52 of the fitting 14 by an amount
54 permitting the insertion of a pry between the
parts 50 and 14 to force the plug 20 away from
60 its seat. In order to prevent any tendency of
the plug 20 to turn when cam 30 is turned by a
hammer, the arm 50 can be arranged also to coop-
erate with edges 48', 48' which define the inner
portion of the slot before mentioned as having
65 the edges 48, the edges 48' being set closer to-
gether than the edges 48 to keep the arm 50 from
turning.

70 It will be understood that the clean-out aper-
ture for tube 12 has a closure operating means
the same as that described in connection with
tube 10 and also having an arm 46 projecting to-
ward arm 46 of the closure described above, so
that the arm 46 for the closure associated with
75 tube 12 also lies substantially in the plane of
passage 16, but projects in the direction from tube
12 toward tube 10. Both arms therefore lie with-

in the contour of the fitting 14, there being no
waste of space due to projections outside of such
a contour.

We claim:

1. The combination of a closure and an operat-
ing apparatus therefor comprising two helical
forcing means adapted to act in series against said
closure and one of said means having a greater
diameter than the other and both having an angle
80 of inclination less than the angle of friction for
the materials of which they are made, and the
parts of the combination being constructed and
arranged so that the one of said means of less
diameter can exert pressure on the closure irre-
90 spective of the angular position of the other of
said means.

2. An apparatus as set forth in claim 1 and in
which the two forcing means act in alinement.

3. The combination of a closure and an oper-
ating apparatus therefor comprising two sets of
cam surfaces adapted to act in series against
closure and one set having a coarse action rela-
tively to the other, both of said sets of surfaces
95 having angles of inclination less than the angles
of friction for the materials of which they are
made, and the parts of the combination being
constructed and arranged so that the set of sur-
faces having the finer action can exert pressure
100 on said closure irrespective of the relative posi-
tions of the surfaces having the coarser action.

4. An apparatus as set forth in claim 3 and in
which the two sets of surfaces act in alinement.

5. The combination of a closure and an oper-
ating apparatus therefor comprising two sets of
110 relatively movable engaging helical surfaces, one
set having a relatively large pitch and the other
a relatively small pitch, both of said sets having
angles of inclination less than the angles of fric-
tion for the materials of which they are made,
115 and the parts of the combination being so con-
structed and arranged that the set having the
relatively smaller pitch can exert pressure on
said closure irrespective of the angular position
120 of the surface of the set having the relatively
larger pitch.

6. The combination of a closure and an oper-
ating apparatus therefor comprising a bolt ar-
ranged to bear against a cam member, said bolt
and cam member adapted to actuate a plug and
said cam member having a laterally projecting
125 arm adapted to receive a hammer blow, said bolt
and cam member having angles of inclination less
than their angles of friction, and the parts of the
combination being constructed and arranged so
130 that said bolt can exert pressure on said closure
irrespective of the angular position of said arm.

7. The combination of a fitting, a pair of par-
allel pipes connected therewith and having a
passage therein for connecting said pipes, said
fitting having apertures in axial alinement with
said pipes, plugs for closing said apertures, and
means individual to each of said plugs for forcing
135 it into its associated aperture, and including
a cam member having an arm extending in a
plane at right angles to the axis of the one of
said pipes associated therewith, the arms of said
means extending toward each other, the parts of
140 the combination being constructed and arranged
to permit each of said arms to be struck by a
hammer when desired, and threaded bolts for
forcing said cam members against their asso-
ciated plugs, each such bolt and cam member
145 having an angle of inclination less than its angle
of friction and the parts of the combination
being constructed and arranged so that each of
150

said bolts can put pressure on its associated plug irrespective of the angular position of the arm on its associated cam, the fitting having skirts arranged to limit the angular movement of the 5 arms.

8. The method of assembling a fitting having a clean-out aperture and a plug therefor, and having a removable abutment in alinement with said plug, a screw in said abutment in alinement 10 with said plug, and a helical cam intermediate said screw and plug having an angle of inclination less than its angle of friction, and having a short arm arranged to be struck by a hammer when desired which comprises the steps of setting up said screw with a light wrench to bring 15 pressure on said cam and plug, and striking said arm a blow to turn said cam and to thereby increase the pressure on said plug.

9. The method as set forth in claim 8 together with the step of setting up said screw with a heavy wrench to further increase the pressure on the plug.

10. The combination of a fitting adapted to connect two pipe lengths and having a closure associated therewith, and an operating apparatus for said closure comprising two sets of cam surfaces arranged to act in alinement against said closure, one of said sets having a coarse action relative to the other and both sets having constant angles of inclination which are less than the angles of friction for the materials of which they are made.
